UNITED STATES PATENT OFFICE.

JAMES W. BRYCE, OF BLOOMFIELD, NEW JERSEY.

COMPUTING-SCALE.

1,314,631.

Specification of Letters Patent.

Patented Sept. 2, 1919.

Application filed April 14, 1916. Serial No. 91,031.

To all whom it may concern:

Be it known that I, JAMES W. BRYCE, citizen of the United States, residing at Bloomfield, county of Essex, and State of New Jersey, have invented certain new and useful Improvements in Computing-Scales, of which the following is a full, clear, and exact description.

In computing scales, one of the most important considerations is the matter of light weight and small momentum of the load-actuated parts; for the sensitiveness and accuracy of the scale depends in large measure upon such features, as will be readily understood. These points present less difficulty in the common type of scale in which the price or cost of the goods is displayed on a drum or dial, since in that type the moving parts are few and simple and have practically no work to perform; but it is otherwise in scales in which only one number—the price or cost of the goods weighed—is displayed, for example on a series of coaxial numeral wheels each exhibiting one digit of the amount. In machines of this type, in which numerical multiplication is actually performed, the scale must at least set or position a controlling member, which represents one of the factors (the weight of the goods) to be multiplied. Naturally, such member is made as small as possible, and of light material, so as to minimize inertia, momentum, and friction, but the capacity of the scale depends, to some extent at least, upon the capacity of the controlling member or members, and hence the temptation is to increase the size and consequently the momentum and inertia, of such members.

I have accordingly been led to devise my present invention, which has for its object to provide an improved scale of the last-mentioned type, in which the controlling or setting member can be so small and light as to have no appreciable effect of impairing the accuracy of the machine, and yet permit the machine to have a relatively large capacity. To this and other ends the invention consists in the novel features and combinations hereinafter described.

In the preferred form of the invention the so-called controlling member or device (as-

suming only one such member or device to be used) is in the form of a wheel or circular disk of sheet metal, preferably aluminum for the sake of lightness as well as strength and stiffness, which is rotated by the movement of the scale pan under the weight of the goods placed thereon. At or near its periphery the disk is provided with one or more series of apertures, and back of the disk I provide one or more circular series of pins which can be moved up (manually) into coöperation with the disk. The pins and the apertures are arranged on the principle of the vernier scale. For instance, ten pins, spaced equidistantly, may occupy the space of eleven apertures. In such case the "reading" of the scale will be to one-ninth of the space between two successive apertures, or one-tenth of the space between two successive pins. The pins are capable of slight axial movement independently of each other, so that when they are carried against the disk the pin that is in register with one or another of the apertures can pass into the same while the others are arrested. Then the pin that passes through a perforation is the one that determines the subsequent operation of the computing or registering mechanism.

One form of the invention, embodying the feature outlined above, is illustrated in the accompanying drawings, in which—

Figure 1 is a side view of the scale mechanism, the housing being in vertical section.

Fig. 1^a is a detail view of a portion of the controlling disk, illustrating the preferred method of balancing the same.

Fig. 2 is a vertical section on a plane immediately in front of the parts shown in Fig. 1.

Fig. 3 is a detail view, on a larger scale, of the parts shown in the upper portion of Fig. 1.

Fig. 4 is a sectional side view of the parts shown in Fig. 3, on the same scale, the pins 22, 23, 24, and some of the supporting studs 20, being omitted for the sake of clearness.

Fig. 5 is a detail view, in vertical section, of the lower portion of the controlling member and the annular pin-carrier, showing

the relation of the contact pins when the latter are in initial position.

Fig. 6 is a detail view similar to Fig. 5 but showing the pins after they have been 5 shifted axially into co-operation with the controlling member.

Fig. 7 is a detail sectional plan view showing the numeral wheels and the segmental gears and ratchets by which they are 10 rotated.

Fig. 8 is a detail side view showing the relation of the numeral wheels and their actuating ratchets and gears, and the electromagnetic mechanism by which the movement of the ratchets are controlled. 15

Fig. 9 is a diagram showing the wiring of the electrical portions of the machine.

Fig. 10 shows the apertured controlling disk or wheel in its initial or zero position, 20 and Fig. 11 shows the same in an advanced position. The disk illustrated is graduated (that is, apertured) to give the total price or value of the goods on the scale pan at a certain price per pound but is rotated in 25 proportion to the weight of the goods or load.

Figs. 12 and 13 are similar views of a controlling disk which is designed merely to give the weight of the load on the pan, with- 30 out regard to price.

Fig. 14 is a detail perspective view.

Fig. 15 is a detail elevation showing a modification of the controlling mechanism, and

35 Fig. 16 is a detail section of the same.

The scale pan 10, Fig. 1, is mounted on a scale beam 11, supported at one end by the fulcrum or pivot 12 and at the other by a spring 13. The vertical rack 14, connected 40 pivotally with and reciprocated by the scale beam, meshes with a pinion 15 and thereby rotates the controlling disk 16 which is rigidly mounted on the same shaft as the pinion, said shaft being indicated at 17. See 45 also Fig. 4. It will be understood that the parts are so designed and proportioned as to make rotary movement of the disk proportional, in a predetermined ratio, to the downward movement of the pan under the 50 weight of the load thereon. As shown in Figs. 4, 5 and 6, the disk is stiffened by a peripheral flange 18. In front is an annular member 18^a to limit flexure of the disk by pressure from behind. The disk is fully 55 described hereinafter, but at this point it may be stated that the particular disk shown in Figs. 10 and 11 has three circular series of price-apertures,—one series for units (cents), one for tens, and one for hundreds 60 (or dollars).

Back of or alongside of and co-axial with the disk 16 is an annular carrier 19, of insulating material, and mounted on the same by means of the posts 20 is an annular guide

21, made of metal so as to be conducting. 65 The carrier supports three series of axially sliding metal pins, 22, 23, 24. The pins are fitted in individual metal guides, as 25, and extend through but are insulated from the metal guide 21. Each pin is provided with 70 a metal button 26 and with a light coil spring 27 to hold the pin normally with its button in contact with the metal guide 21, and the several pins are electrically connected as by wires 28 to individual contacts 29 75 (see Fig. 8 and also the wiring diagram, Fig. 9), there being one contact for each pin, while the guide 21 constitutes a bus-bar providing a common return to the battery or other source of current 30. The carrier 19, 80 with the three series of contact pins, slides on rails 31, 32, toward and from the apertured disk. If when the pins are collectively brought up against the disk any pin finds an aperture in its path, that pin will 85 pass on into the same and the electrical connection between the pin and guide or bus-bar 21 will not be broken. See, for instance, pins 23 and 24, in Fig. 6. On the other hand, the other pins, as for instance pin 22, Fig. 6, 90 will be arrested, the guide 21 will continue its movement, and the electrical connection between the guide and the arrested pin will be broken. The three series of fixed contacts 29, Figs. 8 and 9, are arranged in the arc of 95 a circle and have movable contacts or wipers 33, carried by pivoted ratchets, one of which is shown at 34, Fig. 8. Below the ratchets are three magnets 35, connected to the respective wipers 33 and in multiple with each 100 other to the guide bus-bar 21. Consider now the three pins which are shown in contact with the bus-bar 21 in Fig. 9. Evidently, the three contacts 29^a, 29^b, 29^c, in circuit with the said pins, will be "energized" or 105 "alive", so to speak, when the circuit through source 30 is closed. Then when the wiper at the left (Fig. 9) reaches contact 29^a the magnet 35 below will be energized, thereby 110 throwing its pawl 36 into engagement with the particular ratchet-tooth that has been brought opposite the pawl by the swinging movement of the ratchet, as in Fig. 2 for example. The latter is thus brought to rest at a position depending upon the particular 115 pin (of the associated series of pins) that met an aperture in the controlling disk and was thereby permitted to maintain its electrical connection with the bus-bar 21. In like manner the other ratchets are arrested 120 in correspondence with the operation of the pins of their two series.

The three ratchets 34 are geared individually (see Figs. 7 and 8) to three numeral or digit wheels 37, bearing the proper 125 digits on their peripheries; and since the movements of the ratchets are determined in extent by the movements of the pins 22, 23,

24, which latter movements are determined by the rotation of the controlling disk 16, it will be clear that the particular numerals or digits displayed by the wheels 37 likewise depend upon the movement of the controlling dial. In short, the amount displayed on the digit wheels depends (for any given price-per-pound) upon the weight of the load on the scale pan.

10 The carrier 19, guide or bus-bar 21, and the three series of pins 22, 23, 24 (the whole of which can be conveniently termed an annular "pin box") are shifted back and forth on the rails 31, 32 by means of arms 15 38 (Figs. 3 and 4) on a vertical shaft 39. On the lower end of the latter is a bevel pinion 40 (Fig. 1) meshing with a segmental bevel gear 41 which is rocked by a cam 42, rotated by means of a handle or 20 crank 43 outside of the housing 44 but fixed on the cam shaft 45, so that when the crank is revolved by the operator the shaft 39 will be rocked and the pin box brought up against the controlling disk 16.

25 The ratchet segments 34, Figs. 2 and 8, are actuated in the clockwise direction (as seen in the figures named) by separate coil springs, of which one is shown at 46, but are normally held at their initial or zero 30 positions (Fig. 8) by a universal bar or detent 47 extending through an arc-shaped slot 48 in each ratchet. The detent is carried by an arm 49, Fig. 2, mounted loosely on the shaft 50 on which the ratchets are 35 also loosely mounted, and is connected by a vertical link 51 to an arm 52, pivoted on the shaft 68 and provided with a stud 53 for coöperation with a cam 54 which is fixed on shaft 45. Remembering that the 40 shaft is rotated by the crank or handle 43, Fig. 1, it will be seen that when the shaft is turned the cam releases the arm 52 and so permits the ratchets to move, carrying the detent 47 with them. The shaft 45 always rotates in the direction of the arrow 45 on the cam 54, Fig. 2. In this figure the parts are shown in the positions which they occupy after the computing operation has been 50 performed and the parts are returning (or are about to be returned) to home or initial position. As the cam 54 continues its movement in the direction of the arrow it depresses arm 52 (by engagement with stud 53), thereby rocking arm 48 and retracting 55 the universal bar or detent 47 in the counterclockwise direction. As the bar 47 is retracted, it picks up, one after another, such of the ratchets as were advanced, and restores them, and the associated numeral 60 wheels, to initial position. Clearly, any ratchet is free to swing until arrested by its magnet, and none of the ratchets affects any of the others.

The circuit through the bus-bar 21, source

30, and magnets 35 is normally open at the 65 spring contacts 55, Figs. 2 and 9. At the proper instant a cam 56, fixed on the shaft 45, depresses arm 57. This arm, being rigidly connected to arm 58, depresses the latter and so closes the contacts. In order 70 to economize current, provision is made for locking the magnet armatures 59, which operate the locking pawls 36, as soon as they are all actuated by their magnets, so that the circuit can then be broken at contacts 75 55. For this purpose a hooked pawl or locking dog 60 is provided for each armature, held normally in operative position by a light spring 61. When the armature is drawn over by its magnets, against the 80 tension of its restoring spring 62, it is engaged and held by its locking dog. Eventually, of course, the armatures must be released. For this purpose the dogs, which are loose on the shaft or fulcrum 63, are 85 crossed by a short universal bar (Fig. 8) 90 carried by an arm 65 on the same shaft. This arm is connected by a link 66 (Fig. 2) to an arm 67 loose on shaft 68 on which arm 52 is mounted. A cam 69, fixed on the 95 cam shaft 45, coöperates with a stud on the end of arm 67 and at the proper time depresses the latter, thereby swinging the locking dogs down and out of engagement with the armatures 59; whereupon the armatures are retracted by their springs 62. This operation requires but an instant, and as soon as the armatures have been retracted 100 the rise on cam 69 passes the stud on arm 67, thus permitting the springs 61 to restore the dogs to their operative positions.

The parts are shown in initial position in Fig. 2. In this position the amount last computed is still displayed on the numeral or price wheels 37, Figs. 2 and 7. When the 105 next load is placed on the pan the controlling disk or wheel 16, Figs. 1 and 4, is rotated to a new position. The operator then turns the crank 43, Fig. 1, to rotate the cam shaft 45 in the direction of the arrow on 110 cam 54, Fig. 2. The first effect of rotating the cam shaft is to depress arm 67, thereby releasing the locking dogs 60. Then cam 54 depresses arm 52, driving down link 51 and rocking counterclockwise the arm 49 which 115 carries the universal bar or detent 47. This swings the ratchets or sectors 34 back to initial position, displaying 0.00 on the numeral or price wheels 37. Cam 42, Fig. 1, now rocks the sector 41, which rocks shaft 39 120 and through the agency of arms 38, Figs. 3 and 4, brings the "pin box" 19 up against the disk 16. In this operation the rim of the disk engages the pointed alining or justifying stud and so locks the disk in the position to which it was brought by the load on the scale pan. Cam 56, Fig. 2, now rocks levers 57-58, thus closing the contacts 125 55.

and energizing a contact in each of the series 29, Fig. 9. The cam 54 now permits the ratchets or toothed sectors 34 to swing clockwise (Figs. 2 and 8) under the influence of 5 their actuating springs 46, thereby carrying the wipers or movable contacts 33 down over the fixed contacts 29. As the sectors move, they rotate the numeral wheels from the zero position (to which they have been brought 10 at the beginning of the operation, as described above) and as each moving contact reaches a live contact 29 the corresponding magnet 35 is energized, thereby locking the sector and the pawl 59—36. Cam 42 now 15 retracts the pin box 19 to initial position, and cam 56 permits the contacts 55 to open. The cycle is then completed, with the numeral wheels 37 showing the price of the goods just weighed.

20 Referring now to Figs. 10 and 11, it will be observed that at about the center of the rim of the wheel or disk is a circular series of perforations *a*, sixty in number (fifteen in each quadrant). These holes are spaced 25 equidistantly, in the present instance six degrees of arc apart, and it is assumed that the machine is so designed that a sixty-degree movement of the disk corresponds to one dollar's worth of goods at a certain rate 30 per pound. What that rate may be is at present immaterial. The characters 0¢, 1¢, 2¢ . . . 9¢ (zero cents, one cent, two cents, etc.) designate the ten pins of the circular series 23, Fig. 6. Pin 1¢ is beyond the 35 eleventh 10-cent space (that is, in the direction of movement of the disk as indicated by the arrow) far enough for a disk-movement of one-tenth of a space to bring the adjacent aperture *a*¹ into register with the pin. Then 40 the corresponding contact A¹, Fig. 9, will be energized, and accordingly the units numeral wheel 37, (Fig. 7) will be turned nine steps, thereby displaying the numeral one in the units column. Similarly, a disk-movement of two-tenths of a space will bring 45 aperture *a*² (which is the twenty-second aperture, beginning with the one at the top and counting in the clockwise direction) in register with pin 2¢, and hence contact A², Fig. 9, will then be energized, with the result 50 that the numeral 2 will be displayed in the units-place or column. (This two-tenths movement may or may not be sufficient to carry hole *a*¹ past pin 1¢, but that is immaterial, since the contact A² is ahead of A¹ and hence the numeral wheel will be arrested as soon as A² is reached by the moving contact or wiper. In other words, it is the highest of the energized or live contacts 55 that determines the operation of the numeral wheel.) In like manner, each one-cent increment of movement of the disk brings the next pin into operation. The 5¢ pin, it will be observed, co-operates with the fifty-fifth

hole. Continuing the counting in the same 65 direction, the 6¢ pin co-operates with the sixty-sixth hole, pin 7¢ with the seventy-seventh, pin 8¢ with the eighty-eighth, and pin 9¢ with the ninety-ninth. Moreover, at 70 each whole-space movement of the wheel a new series of holes, previously unused, comes into operation. For instance, if the wheel is turned 1.1 of a space, pin 1¢ then co-operates not with the hole marked *a*¹ in Fig. 10 but with the hole marked *a*¹¹. In this way, 75 by overlapping the series of holes, so to speak, I make sixty wide spaces do the work that would otherwise require six hundred such spaces. Furthermore, to give the same 80 degree of certainty or accuracy of operation the spacing in the six hundred holes would have to be the same as in the sixty holes. In other words, by "interlocking" the several series of holes I make a small wheel do 85 the work of one ten times as large. 85

It will be understood that, mathematically, speaking, the successive pins, as, for example, the 0¢, 1¢, 2¢ pins, etc., follow each other in numerical order. Preferably, also, they have this arrangement in the physical 90 embodiment of this scheme; but it will be seen on a little reflection that the regular order of succession need not be followed. For instance, the 3¢ pin might be between the 1¢ pin and the 2¢ pin, if it be properly 95 spaced from the aperture with which it should co-operate when the disk has turned .3 of a space.

Outside of the series of perforations *a* is a circular series of six equidistant elongated apertures, or slots, *b* each equal in extent to nine-tenths of a ten-cent space (that is, a space between two successive perforations *a*) and preferably each radially opposite such a space. The slot *b*¹, for instance, has its forward end preferably in register with hole *a*¹¹, and extends backward nine-tenths of the space. Slot *b*² then has its forward end registering with hole *a*²², and extends backward nine-tenths of the 110 space, and so on around the disk. The characters 00¢, 10¢, 20¢, etc., designate the pins of the series marked 24 in Fig. 6. The pin 10¢ is in position to co-operate with slot *b*¹, at all positions of the disk between the 115 position for ten cents and nineteen cents. Thus if the disk is turned ten-tenths of a space, the ninety-ninth hole will be carried past pin 9¢ but the forward end of slot *b*¹ will be carried into the path of pin 10¢ and the hundredths hole will be carried into the path of pin 0¢. Hence \$10 will be displayed on the cents wheel 37. If the wheel is turned eleventh-tenth of a space, slot *b*¹ will still register with pin 10¢, but in addition, hole *a*¹¹ will register with pin 1¢, and accordingly \$11 will be displayed; and so on until 19 is reached. At the next step (mean-

ing a disk-movement of twenty-tenths of a space) slot b^1 is carried beyond pin 10¢, but now the forward end of slot b^2 comes into the path of pin 20¢. In like manner the 5 remaining tens-slots come into coöperation with the remaining tens-pins respectively. At the \$.50 to \$.59 positions of the disk, slot b^5 is in the path of pin 50¢. The slot-series now "overlaps," so that at the \$.60 to \$.69 10 positions of the disk the slot marked b becomes slot b^6 and registers with pin 60¢. From \$.70 to \$.79, slot b^1 acts as slot b^7 and coöperates with pin 70¢, and so on. From \$.90 to \$.99, slot b^3 acts as b^9 and coöperates 15 with pin 90¢.

Inside of the series of holes a , is a single opening in the form of a cutaway portion c , extending over an angular distance equal to .99 of ten spaces between holes a . The 20 characters \$.0, \$.1, \$.2, \$.3, etc., designate the six pins of the series 22, Fig. 6. At the \$.99 position of the disk, described above, the forward end of opening c is just in rear of pin \$.1. A one-cent step farther will then bring the forward end of the opening c 25 into register with the pin \$.1., and will carry slot b^3 away from pin 90¢ and carry slot b^5 into register with pin 00¢. At the same time, the hole previously in the path of pin 9¢ 30 will be carried out of register therewith and a hole will be carried into register with pin 0¢. The numeral wheels 37 will then show \$1.00.

Throughout the positions of the disk from 35 \$1.00 to \$1.99, opening c will be in coöperation with pin \$.1. From \$2.00 to \$2.99, opening c will coöperate with pin \$.2, and so on. At the initial position of the disk apertures a^0 , b , and c are in register with pins 0¢, 00¢, 40 and \$0, respectively and hence \$0.00 is displayed on the numeral wheels.

If desired, the disk 16 can be provided with a scale 70, Figs. 10, 11 and 14, visible through an opening 71 in the housing 44 45 toward the operator so that he can read against an index 72 the amount displayed on the numeral wheels 37.

Instead of the price, the machine can be constructed to display the weight of the 50 goods. A controlling disk for this purpose is shown in Figs. 12 and 13, and is designed for pounds, ounces, and half-ounces. In principle it is the same as the price-disk already explained, and detailed description 55 is therefore unnecessary. Suffice it to say that the holes 0, and pins 0 oz., $\frac{1}{2}$ oz., 1 oz., $1\frac{1}{2}$ oz., etc., take care of the ounces and fractions; the slots t , and the pin marked "Tens of oz. pin" take care of the tens of 60 ounces (from 10 oz. to 15 oz.), and the opening p takes care of the pounds, up to, say, ten pounds. The disk may have a scale 73, to enable the operator to read the weight against an index 74. Of course with the disk

shown in Figs. 12 and 13 the numeral wheels 65 could be arranged to display the weight of the load instead of its price or value.

The edge of the flange or rim 18, Figs. 4, 5 and 6, is preferably serrated, with as many notches as there are positions of the disk. 70 Thus in the case of the disk shown in Figs. 10 and 11 and described above, the number of notches would be six hundred. At a convenient position on the annular member 18^a is a pointed pin or stud 75 to coöperate with 75 the serrations. Then when the pin box 19 is brought up against the disk, flexing the latter toward the member 18^a, the stud will engage one of the notches and position the disk accurately "to the nearest cent;" it being understood, of course, that there are ten successive notches or teeth in accurate registry with each space between the centers of two successive perforations a .

It will be observed that the apertures a in 85 the controlling disk constitutes several successive series, each series beginning in rear of the first aperture of the series next preceding. Thus apertures a^0 , a^1 , . . . a^9 , constitute the first series; while apertures a^{10} , 90 a^{11} , etc., constitute the second series, with its first aperture (a^{10}) in rear of the first aperture (a^0) of the first, or next preceding series. So, also, apertures a^{20} , a^{21} , etc., form 95 the third series, beginning in rear of aperture a^{10} of the second series.

If desired, the apertures in the controlling disk can be replaced by electrical contacts, as shown in Figs. 15 and 16, in which 16^c designates the disk, which is overlaid with insulating material. The three series of contacts, indicated by a'_1 , b'_1 , c'_1 , Fig. 16, are arranged and spaced like the corresponding three series of apertures in Fig. 10, and are in electrical connection with a conducting 100 ring or band 75 (through the metal portion of the disk) on which bears a brush or light spring contact 76. The latter, with the wire 77, takes the place of the bus-bar 21, Fig. 9. The carrier 19^c, made of insulating 110 material carries the three series of spring contact-pins 22^c, 23^c, 24^c, which correspond to the third series of pins 22, 23, 24, Figs. 5 and 6, and which coöperate with the contacts on the disk when the carrier and the disk are brought together, as indicated in Fig. 16. A portion of the carrier is shown in elevation in Fig. 15 and the contact-pins in such portion are shown connected to wires marked 10¢, 1¢ \$0, etc., which wires 115 are to be connected to the corresponding contacts 29 in Fig. 9. It will be understood that the magnets 35, Fig. 9, are all to be connected to the wire 77, Fig. 15 through the 120 battery 30. Evidently, when a contact on the disk registers with a contact-pin on the carrier the circuit is completed to the corresponding contact 29, so that when the cor-

responding wiper 33 reaches such contact 29, the particular magnet 35 which is in circuit therewith will be energized and will arrest the corresponding numeral-display 5 wheel 37 as already explained.

The construction described in the foregoing paragraph can be used in a scale, the friction of the brush 76 on the rim 75 being made very light, but it finds its chief 10 utility in computing or like machines in which the disk 16^a is rotated by hand or power to the proper position, corresponding, say, to the product of two factors.

The controlling disks specifically described herein are very nearly symmetrical and hence very nearly in balance, that is very nearly devoid of any inherent tendency to turn in either direction. A simple method of putting the disk in practically 20 perfect balance is shown in detail in Fig. 1^a. For this purpose the spokes of the disk are each slotted lengthwise to receive a small bolt or machine screw 78 with a nut 79. These bolts can be adjusted radially 25 until balance is attained and there secured firmly in position by tightening the nuts.

The stem 10^a, Fig. 1, on which the scale pan 10 is mounted, is maintained in vertical position by means of "parallel movement" 30 mechanism 10^b, to which the stem is connected by an arm 10^c.

It is to be understood that the invention is not limited to the construction herein described. On the contrary it can be success- 35 fully embodied in a variety of widely different forms without departure from its spirit, and in the embodiment illustrated numerous modifications can be made. For instance, it is, in general, immaterial 40 whether the pins are moved up to the controlling member (preferably a disk, as described), or the latter moved up to the pins; or whether the controlling member is moved (rotated, in the present instance) past the 45 pin-box, or vice versa. In the appended claims the pins are said to represent successive digits of a numerical order. Evidently it is immaterial how many units of one order make one unit of the next higher 50 order, and whether the order represented expresses cents, or ounces, etc. Moreover, the size or value of the "unit" may be one cent, or two cents, or five cents, or one ounce or two ounces, etc., depending on the relative 55 spacing of the pins and apertures, just as the vernier of a divided circle may read to one minute or to two or more minutes.

What I claim is:

1. In a scale, the combination with a scale 60 pan to receive the load, and means whereby the pan is so mounted as to be actuated by the load a distance proportional to the load; of a controlling member having a plurality

of controlling apertures; means connecting the controlling member and the pan where- 65 by the latter is movable in correspondence with the pan; a series of pins and a mount- ing therefor whereby the pins are axially movable individually and also movable col- lectively into coöperation with the aper- 70 tured controlling member, the pins and the controlling member apertures being in over- lapping vernier relation; means for carry- ing the pins collectively against the control- 75 ling member whereby any pin in registry with an aperture therein will enter such aperture; and display mechanism controlled by the entering pin.

2. In a scale, the combination with a scale pan to receive the load, and means whereby 80 the pan is so mounted as to be actuated by the load a distance proportional to the load; of a controlling disk having a plurality of series of controlling apertures around its per- 85 phery; means connecting the pan and the disk to rotate the disk from an initial position to an extent proportional to the load on the pan; a plurality of series of pins, one series for each series of apertures in the disk; means whereby the pins are so mounted 90 as to be movable collectively toward and from the disk and also movable independ- ently of each other, the pins of each series and the apertures of each series being spaced in overlapping vernier relation; means for 95 shifting the pins collectively into coöpera- tion with the disk whereby any pin in regis- try with an aperture will enter the same and the other pins be held back; and display mechanism arranged to be controlled by the 100 entering pin or pins.

3. In a scale, in combination, a scale pan to receive the load, and means whereby the pan is so mounted as to be actuated by the load a distance proportional to the load; a 105 rotary disk having the circular series of apertures spaced equi- angularly apart; means whereby the disk is controlled by the pan to rotate in correspondence with the movement of the pan under the influence of 110 the load; a circular series of pins and a mounting therefor whereby the pins are movable collectively toward and from the disk to coöperate with the same and are also movable independently of each other, a 115 number of said pins representing successive digits of a given numerical order, being spaced apart to extend over substantially the space of the entire series of apertures in the disk, and others of said pins represent- 120 ing the remaining digits of said order, fol- lowing the last of the first number of pins, being located between the pins of said first number; means for shifting the pins into co- operation with the disk whereby any pin in 125 registry with an aperture therein will enter

such aperture and the other pins be restrained; and display mechanism arranged to be controlled by the entering pin.

4. In a scale, the combination of a scale 5 pan, and means whereby the pan is so supported as to be actuated by the load a distance proportional to the load; a controlling member having a series of apertures; means for moving the controlling member in correspondence with the movement of the pan; a series of pins spaced in vernier relation to the apertures in the controlling member; supporting means for the pins, permitting movement of the pins individually relatively 10 to the controlling member; means for shifting the pins collectively into coöperation with the controlling member whereby any pin in registry with an aperture in said member will enter such aperture and the remaining pins be restrained; display mechanism; controlling mechanism therefor, having a plurality of electric controlling circuits including said pins; and means enabling current in the circuit of a pin which 15 enters an aperture in the disk to actuate the controlling mechanism.

5. In a scale, the combination of a movable controlling member having a series of apertures, a series of pins in vernier relation 20 to said apertures and movable into coöperation with the controlling member whereby any pin in registry with an aperture will enter the same and the others be restrained, an insulated carrier for said pins, in which 25 they are individually movable and including a conducting member with which they are in electrical connection, the connection through a pin being broken when such pin is restrained from movement by engagement 30 with the controlling member, a plurality of circuits connected with the said conducting member and with the respective pins whereby only the circuits of pins that enter apertures in the controlling member will be 35 closed when the pins are shifted into coöperation with the controlling member, and display mechanism arranged to operate under the control of said circuits.

6. The combination of a circular series of 40 pins representing successive digits of a numerical order; a carrier in which the pins are axially movable independently of each other and by which they may be moved collectively in an axial direction; a rotary disk

having a plurality of successive circular series of spaced apertures concentric with the circular series of pins, the first aperture of each series being immediately in rear of the first aperture of the next preceding series; the pins and each series of apertures being 45 spaced in vernier relation whereby the series of pins coöperates with any of the several series of apertures according to the extent of rotation of the disk, and means for actuating the pin carrier to bring the pins 50 collectively into coöperation with the disk whereby any pin in registry with an aperture therein will enter the same and the other pins be restrained.

7. The combination with a rotary disk 55 having a plurality of overlapping circular series of spaced apertures, all the apertures being in the same circumferential line; of a single circular series of axially arranged pins concentric with the several overlapping 60 series of apertures and spaced in vernier relation to each of said overlapping series of apertures; a carrier in which the pins are individually movable lengthwise; and means for moving the carrier toward the disk to 65 carry the pins collectively into coöperation therewith.

8. The combination with a circular series of pins arranged parallel to each other; an axially movable carrier in which the pins 70 are individually movable in an axial direction; a rotary disk having in a single circumferential line a plurality of equidistant apertures, the number of apertures being an even multiple of the number of pins thereby 75 providing a plurality of series of apertures to coöperate with the series of pins, the series of pins and each series of apertures so provided being in vernier relation; and means for shifting the pin carrier toward 80 the disk.

9. The combination of a disk having a plurality of overlapping circular series of spaced apertures, all the apertures being in the same circumferential line; a single circular series of pins concentric with the several overlapping series of apertures and spaced in vernier relation to each of said overlapping series of apertures; and a support in which said pins are axially mov- 90 able.

In testimony whereof I affix my signature.

JAMES W. BRYCE.
